(57) **CLAIM**

The ornamental design for the data acquisition device, as shown and described herein.

DESCRIPTION

FIG. 1 is a top, front, right side perspective view of a data acquisition device showing my new design;

FIG. 2 is a Top plan view thereof;

FIG. 3 is a Rear elevation view thereof;

FIG. 4 is a Right side, Top perspective view thereof;

FIG. 5 is a Left side, Top perspective view thereof; and,

FIG. 6 is a Front, Top perspective view thereof.

The bottom is not shown and is unornamented and not claimed.

The broken line portions form no part of the claimed design.
